HAIR ROLLER

Kenneth Reiner, Box 54091, Terminal Annex,
Los Angeles, Calif.

Filed Nov. 19, 1962, Ser. No. 72,542

Term of patent 14 years

(Cl. D86—10)

FIG. 1.

FIG. 2.

The characteristic features of my design reside in the combination on the perforated hair roller disclosed of the rows of fluted bands on the outwardly flaring end portions, said bands contrasting in color or shade from the balance of the cylindrical body, substantially as shown.

I claim:

The ornamental design for a hair roller, as shown and described.
